UNITED STATES PATENT OFFICE.

ANDREW HOWARD, OF PITTSBURG, PENNSYLVANIA.

DESIGN FOR A LAMP OR GAS SHADE.

SPECIFICATION forming part of Design No. 19,328, dated October 1, 1889.

Application filed August 13, 1889. Serial No. 320,641. Term of patent 3½ years.

To all whom it may concern:

Be it known that I, ANDREW HOWARD, a citizen of the United States, residing at Pittsburgh, in the county of Allegheny and State of Pennsylvania, have invented a new and original Design for Lamp or Gas Shades; and I do hereby declare the following to be a full, clear, and exact description of the invention, reference being had to the accompanying drawing, which forms part of this specification.

My design for a lamp or gas shade consists in the representation of two separate shades of different outline and different size, one surrounding the other, and the two united by a circular bead.

In the drawing, A designates the shade embodying my design. A' represents the lower half, which is of spherical form, and B the upper half, the walls of which are shaped on an ogee or S curve, terminating in the neck D, of similar curvature, but smaller and re-

versed. At the junction of the neck and section B two beads c c are formed and inclose the narrow portion of the neck, while a single bead d is formed at the junction of sections A' and B. 25

I claim—

The design for a lamp or gas shade, consisting of a shade representing two bowls of 30 different diameters, the lower spherical bowl being surrounded by one of an ogee or S shaped contour, and the latter united to a reversely-curved but similar-shaped neck, beads being located at the junction of the 35 two bowls and of the upper one with the neck, as shown.

In testimony that I claim the foregoing I have hereunto set my hand this 26th day of July, 1889.

ANDW. HOWARD.
